GRINDER

Wilfrid G. Wilson, Fort William, Ontario, Canada

Application December 20, 1944, Serial No. 569,048

4 Claims. (Cl. 51—100)

1

This invention relates to certain novel and useful improvements characterizing what is believed to be a highly useful and practicable grinder which is especially, but not necessarily, adapted for use in the making of templates and dies which vary in thickness.

More specifically, the grinder with which we are herein concerned is designed to eliminate long and costly hand filing, this due to the fact that the present machine, because of its particular design and functional achievements makes it possible to do better what was heretofore done tediously and slowly by way of the customary hand filing technique.

Briefly, the preferred embodiment of the invention comprises a base plate adapted to receive the work, a perpendicular post rising therefrom, a motor-equipped arm and adapter bracket means for properly mounting same on the post, and an adjustable arm also on the post above the grinder, this having appliances to accommodate the pattern to be followed in grinding operations.

Novelty is thought to reside in a collar which is adjustable on the post, the inner adjacent portion of the grinder arm coacting therewith, the arm itself being swung back and forth like a human arm and being provided with a motorized grinding tool and suitable maneuvering and manipulating handles.

Novelty is also predicated upon the adoption and use of a feeler or tracer element carried by the swingable arm, this being arranged to cooperate with special adapter means which clamps and holds in place the pattern or so-called lay-out template.

Other features and advantages will become more readily apparent from the following description and the accompanying illustrative drawing.

In the drawing, wherein like numerals are employed to designate like parts throughout the views, the single figure is a perspective view of a grinder constructed in accordance with the principles of the present invention.

Referring now to the drawing by distinguishing reference numerals, it will be seen that the base, which is of appropriate configuration, is denoted by the numeral 5. This is provided with suitable supporting legs, marginally arranged, is approximately 14" x 20" in length and is provided with a flat area 6 which supports the work (not shown). This region 6 is provided with spaced longitudinal slots 7. Attached to and rising from the socket 8 is an upright which may be con-

2

veniently referred to as a post 9. A collar 10 is mounted on the post and provided with binding lugs 11 rendered effective by clamping means 12. The numeral 13 designates a motor, that is an electric motor, of any suitable style and type, on the outer end of the horizontal swinging arm 14. The motor is provided with a concentric grinding tool 15 and on diametrically opposite sides with claw-like handles 16, these to permit proper handling and maneuvering of the tool 15. The arm 16 is connected to a hinging and adjusting ring 17 which in turn is connected by a rule joint 18 to the arm 14. Thus, the desired swinging, adjusting and hinging action for the motorized tool is provided.

Referring further to the swingable arm and tool assembly, it will be noted that this is flat on top to accommodate a channel-shaped clip 19 which serves to accommodate a shiftable block 20 held in place by a set-screw 21 and carrying a feeler wheel 22 sometimes also referred to in the art as a tracer.

I next call attention to the horizontal arm 23 having a collar 24 at its inner end with clamping lugs 25 and clamping means 26 whereby to permit the arm to be adjusted up and down and in a horizontal plane to properly locate the adapter means on the outer end thereof. The adapter means comprises a slide 27 held in place by a set screw 28, said slide having a depending portion with a horizontal slotted frame 29. This frame serves to accommodate the pattern or lay-out template (not shown), that is the part which is to be traced by the feeler wheel 22. Retaining elements 30 held in place by wing nuts 31 I employ to securely mount the pattern.

As before stated, the machine is designed to eliminate long and costly hand filing. The template used is a lay-out template; of $\frac{1}{2}$ " sheet-metal. The grinder is used for making templates and dies which vary in thickness. This lay-out template has always been made for jobs by hand. The use of the novel machine for accomplishing the results is a step forward in the art.

45 The work, which is to be ground, is first sawed on a "Do-all" saw to within $\frac{1}{2}$ " of finished lines and is then finished on my improved grinder. The work is fastened in the slots and the grinder arm is lowered so that the tool can operate properly. The grinder tool arm is held in place by the stop collar 10 and correct shape is given to the work on the base by a lay-out template held in place by the wing nuts 31, the different contours being followed by the feeler wheel or tracer. 50 The grinder arm and tool is swung similar to a

man's arm in action. Grinder wheels can be changed for different thickness of material. The machine is very simple design and would not be very costly to make. Moreover its use will result in greatly speeding up work done on dies and templates.

A careful consideration of the foregoing description in conjunction with the invention as illustrated in the drawing will enable the reader to obtain a clear understanding and impression of the alleged features of merit and novelty sufficient to clarify the construction of the invention as hereinafter claimed.

Minor changes in shape, size, materials and rearrangements of parts may be resorted to in actual practice so long as no departure is made from the invention as claimed.

I claim:

1. A grinder of the class described comprising a base, a post attached to and rising vertically from said base, a stop collar adjustable on said post, an arm provided with a ring surrounding the post and cooperable with the stop collar, a motor on the outer end of the arm, and a tool carried by said motor, the arm being attached to said ring by way of a rule joint, said motor being provided with diametrically opposite claw-like handles and being provided on its top with a clip, a block slidable in said clip, and a feeler wheel mounted on said block.

2. A grinder of the class described comprising a base, a post attached to and rising vertically from said base, a stop collar adjustable on said post, an arm provided with a ring at its inner end surrounding the post and cooperable with the stop collar, a motor on the outer end of said arm, a tool carried by said motor, said arm being attached to said ring by way of a rule joint, handles mounted on diametrically opposite sides of said motor, and a feeler wheel slidably and adjustably mounted on said motor.

3. A grinder of the class described comprising a base, a post attached to and rising vertically from said base, a stop collar adjustable on said post, an arm provided with a ring at its inner end surrounding the post and cooperable with the stop collar, a motor on the outer end of said arm, a tool carried by said motor, said arm being attached to said ring by way of a rule joint, handles mounted on diametrically opposite sides of said motor, a feeler wheel slidably and adjustably mounted on said motor, a second arm adjustably mounted on said post above the first-named arm, said second arm being provided on its outer end with adapter means, said adapter means being constructed to accommodate a pattern to be traced, said adapter means including a bracket and said bracket being slotted and provided with wing nut equipped clamping elements for a lay-out template.

4. A grinder of the class described comprising a base, said base embodying an upstanding plate having a marginal depending flange, said plate being provided with a plurality of parallel spaced slots, a vertical post attached to and rising from said base, a horizontal arm adjacent the upper end of said post swingably and adjustably mounted on said post, said arm being provided at its outer end with an adjustable bracket and said bracket being slotted and provided with wing nut equipped clamping elements for a lay-out template, a stop collar adjustable on said post, a second arm provided with a ring surrounding the post and cooperable with the stop collar, a motor on the outer end of the arm, a tool carried by said motor, said latter arm being attached to said ring by way of a rule joint, said motor being provided with diametrically opposite handles, and a feeler wheel mounted on the top of the motor beneath said slotted bracket and above said handles.

WILFRED G. WILSON.
